METHOD OF MAKING PAVEMENT CONFORMATION

Filed Jan. 8, 1925

FIG. I

FIG. II

FIG. III

FIG. IV

FIG. V

FIG. VI.

INVENTOR:
MATTHEW F. BRAMLEY

by his atty.

Matthew F. Bramley

UNITED STATES PATENT OFFICE.

MATTHEW F. BRAMLEY, OF CLEVELAND, OHIO.

METHOD OF MAKING PAVEMENT CONFORMATION.

Application filed January 8, 1925. Serial No. 1,297.

To all whom it may concern:

Be it known that I, MATTHEW F. BRAMLEY, a citizen of the United States, residing at Cleveland, in the county of Cuyahoga and State of Ohio, have invented a new and useful Improvement in Methods of Making Pavement Conformation, of which the following is a specification, the principle of the invention being herein explained and 10 the best mode in which I have contemplated applying that principle, so as to distinguish it from other inventions.

My invention pertains to the method of making a rail adjoining pavement and more 15 particularly relates to the art of forming a channel along which the flange of a car wheel may travel without coming into contact with the pavement.

Fig. I is a vertical cross-section of a 20 street railway pavement constructed after the manner of my invention.

Fig. II is an enlarged vertical cross-section showing the preliminary concrete embedding of the lower portion of a rail.

25 Fig. III is a view corresponding to Fig. II showing the addition of a soft and heated asphalt surfacing substantially level with the tread of the rail.

Fig. IV is a view corresponding to Fig. 30 III showing a novel element used in carrying out my method, the same being shown compressed into the asphaltum layer inwardly adjacent the head of the rail, which is to say, on the side of the rail nearest its 35 parallel companion rail.

Fig. V is a view corresponding to Fig. 40 IV after complete performance of my method and with the forming element removed.

Fig. VI is a perspective view of the forming bar, the cross-section of which is a rhombus.

A concrete foundation 1, supports a pair 45 of parallel rails 2 which are partially embedded therein so that the heads 3 of the rails project thereabove. Next an asphaltum layer 4 is spread upon the concrete and rolled substantially level with the tread surface of the heads 3 and then, while the asphaltum layer is still soft and warm elongated forming bars 5, preferably of metal, are pressed into the asphaltum layer inwardly adjacent or on the near sides of parallel rails until the upper surfaces of the 50 bars rest substantially flush with the upper

surface of the asphaltum layer and about 55 level with the tread portion 3 of the rail as appears in Figure IV.

It will be observed that the forming bar 60 is of peculiar cross-sectional shape having in fact a cross-section which is a rhombus. It is to be noticed also that the upper and lower sides of the bar 5 are approximately horizontal whereas the other two sides 6 65 recede in an upward direction with respect to the abutting rail head. After a suitable interval of time the forming bars 5 are pried loose to leave the channels 7 inwardly adjacent a rail in which the flange 8 of a car wheel 9 may freely move by longitudinal travel therealong and within the expectable 70 range of lateral or swaying movement.

I claim:

1. The method of making a rail-adjoining pavement which consists in laying an induratable pavement alongside of and 75 against one entire side of the head of a rail, pressing any sides of a metal member of symmetrical shape into said pavement to displace a portion of said pavement away from the upper side portion of the rail and 80 later removing said member.

2. The method of making a rail-adjoining pavement which consists in laying an asphalt pavement adjoining a rail, pressing a 85 symetrically shaped and reversible metal member into said pavement while soft, allowing the pavement to harden against said member and finally removing said member to leave a channel between said rail and the pavement for the passage of a car wheel 90 flange.

3. The method of forming a channel in a railway pavement suited to the rolling passage and side sway of a car wheel flange 95 which consists in temporarily embedding in an indurating pavement and alongside of the rail location a member rhomboid in cross-section.

4. The method of making a rail-adjoining pavement which consists in laying an induratable pavement alongside of a rail, imbedding a member, the cross section of which is a rhomboid, into said pavement alongside of a rail while said pavement is soft and finally removing said member.

Signed by me, this 9th day of December, 1924.

MATTHEW F. BRAMLEY.
